ATTORNEY.

UNITED STATES PATENT OFFICE.

MUNRO S. BROWN, OF GOLDFIELD, NEVADA.

SELF-LIGHTING CIGARETTE.

1,327,139.

Specification of Letters Patent.

Patented Jan. 6, 1920.

Application filed May 8, 1919. Serial No. 295,639.

To all whom it may concern:

Be it known that I, MUNRO S. BROWN, a citizen of the United States, residing at Goldfield, in the county of Esmeralda and State of Nevada, have invented Self-Lighting Cigarettes, of which the following is a full and complete specification.

My invention is an improvement in cigars and cigarettes, and has particular reference to providing a cigarette with igniting means in the form of a tip at the end thereof whereby it may be readily and conveniently lighted without requiring the use of a match. Those accustomed to the use of cigarettes quite frequently are in the unfortunate situation of having a plentiful supply of cigarettes but without any means of lighting one, and under the circumstances are deprived of the pleasure of smoking until a light can be obtained. Then again, wind conditions sometimes make it difficult to keep a match lighted until the cigarette can be lighted therefrom.

Therefore it is for the purpose of providing an unfailing medium by which the cigarette may be lighted that I provide the end of the cigarette with a small tip of igniting material applied in such manner that it will be efficient in effecting the lighting of the cigarette and at the same time will not materially increase the bulk or diameter of the same at the end and thus permit a number of cigarettes supplied with the igniting means to be packed closely and evenly in a box or container, as usual.

It is also my purpose, in the present instance, to make the igniting-tip of a composition such as employed in the manufacture of the ordinary safety-match so that it can be ignited only in coöperation with the usual phosphoric surface, the latter being similar to that applied to the box containing safety-matches but in the present instance applied to the box or container in which the cigarettes are packed; whereby accidental ignition of the tip may be prevented.

My invention contemplates applying the igniting-tip to the end of the cigarette in the particular manner hereinafter set forth, and what I claim as new in the art and desire to

properly protect by Letters-Patent is more specifically set forth in the appended claims.

In the drawings:

Figure 1 is a plan view showing the application of my invention and illustrating a package of cigarettes provided with the igniting-tips.

Fig. 2 is a detail view of a cigarette supplied with an igniting-tip in accordance with my invention.

Fig. 3 is a similar view with the outer end of the cigarette in section to show the disposition of the igniting-tip with respect to the tobacco and paper tube or wrapper.

Figs. 4, 5 and 6 illustrate the different steps which are employed in applying and forming the tip in the end of the cigarette.

In view of the character of the ordinary cigarette made to comprise a paper tube and filling of tobacco it is important that the igniting tip be applied to the end of the cigarette in such manner that it will hold firmly in place and not become detached in the operation of striking it across the cooperating phosphoric surface, and it is also an important consideration that the bulk of the cigarette should not be materially increased to prevent a quantity of cigarettes from being neatly packed in a box or container as usual; but of course it is necessary that a sufficient quantity or bulk of the igniting material should be applied to effect the proper lighting of the cigarette.

In the drawings I have shown my invention applied to the ordinary form of cigarette, composed of a paper tube 5, filled with tobacco 6, of the character commonly known as machine-made cigarettes; although of course it will be obvious that the same may be applied to all-tobacco cigarettes, and cigars.

In carrying out my invention the igniting-tip 7 is applied to one end of the cigarette so as to become an intimate part of the same, being bulbous or practically semi-spherical in shape and of a diameter corresponding substantially with that of the cigarette at its end, the inner side of the semi-spherical or bulbous tip being next to the tobacco filling so as to closely adhere therewith while

the curved surface is outermost for contact with the coöperating phosphoric surface across which said tip is rubbed to ignite the same.

5 The igniting-tip is composed of the material usually employed in making the heads of safety-matches, and as such compositions are well known a particular description of the same herein is not considered necessary; 10 but inasmuch as I preferably form the igniting-tip on the end of the cigarette by dipping the latter into the material, as herein-after described, the consistency of said material must be such as to properly adhere to 15 the tobacco filling and paper tube or wrapper and also assume a globular or extended form after being removed from the material.

The operation of forming the igniting-tip on the end of the cigarette is illustrated in 20 Figs. 4, 5 and 6 of the drawings, by reference to which it will be seen that the end of the cigarette is first dipped into the liquid-mixture 8, in trough 9, (Fig. 4), then removed, which will leave a comparatively 25 thin coating of the liquid-mixture at the end of said cigarette, as indicated in Fig. 5, and in a very short while said coating or small batch of the igniting mixture will assume the extended or globular shape shown in 30 Fig. 6 and harden. Of course the whole operation consumes but a very short period of time, according to the nature of the igniting composition or its hardening propensity; and it will be understood, also, that the several steps of the operation may be accomplished by a suitable apparatus (not shown), but which may be devised and applied as an 35 attachment to any type of cigarette-machine. As the material which adheres to the end of the cigarette in the dipping operation assumes the extended or globular shape after being removed from the mixture it flows away from the sides of the end of the cigarette so that the completely formed and 40 hardened igniting-tip will not extend beyond said sides to any material extent and thereby interfere with the packing of the cigarettes neatly in the container, and the body of the tip will project only a slight distance from the end of the cigarette so that it 45 will not detract from the general appearance of said cigarette.

When a machine-made cigarette is manufactured there is usually a small space left in 50 each end of the paper tube or wrapper beyond the tobacco filling, and therefore when one end of the cigarette is dipped to receive the small batch of igniting-material the latter will enter this space and with the thin 55 film that is left on the outside of the paper tube after the tip is formed and hardens will serve to securely connect said tip to the cigarette; the connection or attachment being materially augmented by the mixture pene-

trating into and being incorporated with the shreds of tobacco-filling at the extreme end of said filling. In such instances that in the manufacture of the cigarette the tobacco filling should extend to the extreme end of the paper-tube or nearly so it would be necessary 65 to form the space hereinbefore referred to by punching the tobacco into the tube or wrapper a slight distance as by the perforated plate 12, Fig. 4; for, as already explained 70 the embedding of the paper tube or wrapper into the hardened igniting-tip attaches the latter firmly and securely to the cigarette so that it will not become detached when rubbed across the surface which coöperates 75 in igniting said tip.

The operation hereinbefore described 80 would be carried out in forming the igniting-tip on the end of an all-tobacco cigarette or cigar, and in these instances the wrapper of the cigarette or cigar would be embedded 85 in the hardened tip in the same manner as in the case of the paper-tube.

The striking surface for the igniting-tip, composed of the material used on the boxes for safety-matches, may be applied anywhere on the package in which the cigarettes are packed, but I prefer to apply the same across the lower end of the front or back of the package, where it will not only be convenient for striking off the tipped-cigarette 90 but such location is less likely to result in its becoming broken in the handling of the package. Fig. 1 of the drawing shows this disposition of the striking surface, in which 95 10 designates the package, and 11 the striking-surface.

The operation of lighting a cigarette provided with an igniting-tip as herein described will be readily understood, inasmuch as said operation is precisely like that of 105 striking an ordinary safety-match, the body of the cigarette being held in the same way as the stem of the match is held as the tip is drawn across the coöperating igniting surface on the package.

The cigarettes are packed preferably with the tipped-ends toward the bottom of the package, as shown in Fig. 1, so as to not only 110 better protect the tips when the package is opened but also that the cigarettes as drawn from the package will be in proper position in the hand for striking on the surface to ignite said tip.

The addition of the igniting-tips to an end of the cigarettes will not add materially to 115 the cost of a package of cigarettes, and the convenience of having the means for producing a light will prove of great advantage in many situations where a match may be hard to obtain or where it may be difficult to 120 keep a match lighted.

Having described my invention, I claim:

1. In combination with a cigarette of a tip

of igniting material extending into one end of the paper tube or wrapper and slightly penetrating the tobacco filling with a thin film of the igniting material around the outer side of the paper-tube or wrapper whereby the latter and shreds of the tobacco filling are embedded in said tip.

2. In combination with a cigarette comprising a tube and filling of tobacco with a

space within the outer end of the tube, of 10 igniting material introduced into the space at the outer end of the tube and around the outer side of the latter and so that said material penetrates the tobacco filling, whereby said igniting material forms a tip securely 15 attached to the end of the cigarette; as herein set forth.

MUNRO S. BROWN.
